CLAIM

The ornamental design for a combined walk-in stairs and built-in spa for swimming pools, substantially as shown and described.

DESCRIPTION

FIG. 1 is a top plan view of a combined walk-in stairs and built-in spa for swimming pools, showing our new design;

FIG. 2 is a front elevational view of a combined walk-in stairs and built-in spa for swimming pools from the opposite side;

FIG. 3 is a perspective view from one side thereof;

FIG. 4 is a perspective view front the other side;

FIG. 5 is a rear elevational view thereof.
